(57) **CLAIM**

We claim the ornamental design for an oral irrigator handle, as shown and described.

DESCRIPTION

FIG. 1 is a front isometric view of an oral irrigator handle with a tip shown for environment.

FIG. 2 is a front isometric view of the oral irrigator handle of FIG. 1.

FIG. 3 is a front elevation view of the oral irrigator handle of FIG. 2.

FIG. 4 is a rear elevation view of the oral irrigator handle of FIG. 2.

FIG. 5 is a left side elevation view of the oral irrigator handle of FIG. 2.

FIG. 6 is a right side elevation view of the oral irrigator handle of FIG. 2.

FIG. 7 is a top plan view of the oral irrigator handle of FIG. 2; and,

FIG. 8 is a bottom plan view of the oral irrigator handle of FIG. 2.

The broken line showing of the irrigator tip in FIG. 1 illustrates environment and forms no part of the claimed design. All other broken lines illustrate portions of the oral irrigator handle that form no part of the claimed design.
